UNITED STATES PATENT OFFICE

144,874

DESIGN FOR A CHILD'S WHEELED TOY

Robert L. Schultz, Lorain, Ohio

Application September 4, 1945, Serial No. 121,822

Term of patent 14 years

(Cl. D34—15)

To all whom it may concern:

Be it known that I, Robert L. Schultz, a citizen of the United States, residing at Lorain, in the county of Lorain and State of Ohio, having invented a new, original, and ornamental Design for a Child's Wheeled Toy, of which the following is a specification, reference being had to the accompanying drawing, forming a part thereof, in which:

Fig. 1 is a perspective view of a child's wheeled toy showing my new design;

Fig. 2 is a top plan view of the child's wheeled toy shown in Fig. 1, on a reduced scale; and

Fig. 3 is a side elevational view of Fig. 2.

The essential features of the child's wheeled toy reside in the portions shown in full lines on the drawing.

I claim:

The ornamental design for a child's wheeled toy, substantially as shown and described.

ROBERT L. SCHULTZ.
